UNITED STATES PATENT OFFICE.

CONRAD R. STRASSNER, OF LYNBROOK, NEW YORK, ASSIGNOR TO ATLANTIC KNITTING MILLS, OF NEW YORK, N. Y., A CORPORATION OF NEW YORK.

DESIGN FOR A KNITTED FABRIC OR SIMILAR ARTICLE.

Application filed April 28, 1923. Serial No. 5,993. Term of patent 3½ years.

To all whom it may concern:

Be it known that I, CONRAD R. STRASSNER, a citizen of the United States of America, and resident of the city of Lynbrook, county of Nassau, State of New York, have invented a new, original, and ornamental Design for a Knitted Fabric or Similar Article, of which the following is a specification, reference being had to the accompanying drawing, forming part thereof.

The figure is a plan view of a knitted fabric or similar article, illustrating my new and ornamental design.

I claim:

The ornamental design for a knitted fabric or similar article, as shown.

CONRAD R. STRASSNER.
